GUIDED MISSILE

William Hunter A. Boyd, Kensington, Md., assignor to
the United States of America as represented by the
Secretary of the Navy

Application May 6, 1949, Serial No. 2,501

Term of patent 14 years

(Cl. D71—1)

FIG. 1

FIG. 2

FIG. 3

FIG. 4

Fig. 1 is a perspective view of a guided missile as it appears when seen obliquely from below and at the front;

Fig. 2 is a perspective view of the guided missile as it appears when seen from one side and slightly from the rear;

Fig. 3 is a perspective view of the guided missile as it appears obliquely from above and at the front, and

Fig. 4 is a rear view of the guided missile.

The design for a guided missile is characterized by the fairing which ornaments the junction of the base portions of the swept-back wings with the fore component of the body at places substantially coincident with the top surface of said body; the rib which merges with the fairing and overlies said component both fore and

aft, and the contrast derived from the attachment of the swept-back empennage from the under side of the aft body component.

What is claimed is:

The ornamental design for a guided missile, substantially as shown and described.
